US0D1113869S

(12) **United States Design Patent** (10) Patent No.: **US D1,113,869 S**
(45) Date of Patent: ** Feb. 17, 2026

(54) **EARPHONE**

(71) Applicant: **BEIJING XIAOMI MOBILE SOFTWARE CO., LTD.**, Beijing (CN)

(72) Inventor: **Yuhao Zhang**, Beijing (CN)

(**) Term: **15 Years**

(21) Appl. No.: **35/522,374**

(22) Filed: **Sep. 14, 2023**

(80) **Hague Agreement Data**

Int. Filing Date: **Sep. 14, 2023**

Int. Reg. No.: **DM/232121**

Int. Reg. Date: **Sep. 14, 2023**

Int. Reg. Pub. Date: **Sep. 20, 2024**

(30) **Foreign Application Priority Data**

Mar. 17, 2023 (CN) 202330128359.7

(51) **LOC (15) Cl.** **14-01**

(52) **U.S. Cl.**

USPC **D14/223**

(58) **Field of Classification Search**

USPC D14/205, 207, 217, 221, 223, 225;

(57) **CLAIM**

The ornamental design for an earphone as shown and described.

DESCRIPTION

1. Earphone
2. Earphone
- 1.1: Front
- 1.2: Back
- 1.3: Left
- 1.4: Right
- 1.5: Top
- 1.6: Bottom
- 1.7: First Perspective
- 1.8: Second Perspective
- 1.9: Third Perspective
- 1.10: Fourth Perspective
- 2.1: Front
- 2.2: Back
- 2.3: Left
- 2.4: Right
- 2.5: Top
- 2.6: Bottom
- 2.7: First Perspective
- 2.8: Second Perspective
- 2.9: Third Perspective
- 2.10: Fourth Perspective

1 Claim, 20 Drawing Sheets
